D. D. HOLMES.

REPLACER FOR ROLLING STOCK OF RAILWAYS.

APPLICATION FILED SEPT. 10, 1921.

1,403,247.

Patented Jan. 10, 1922.

UNITED STATES PATENT OFFICE.

DAVID DWIGHT HOLMES, OF NEW YORK, N. Y.

REPLACER FOR ROLLING STOCK OF RAILWAYS.

1,403,247.

Specification of Letters Patent. Patented Jan. 10, 1922.

Application filed September 10, 1921. Serial No. 499,672.

To all whom it may concern:

Be it known that I, DAVID DWIGHT HOLMES, a citizen of the United States, and a resident of New York city, borough of Manhattan, in the county and State of New York, have invented new and useful Improvements in Replacers for Rolling Stock of Railways, of which the following is a full, clear, and exact specification.

This invention relates to portable devices employed for re-railing locomotives, cars, and other rolling stock that has become derailed, and my improvements are directed to the novel form and contour of such devices whereby they are rendered more efficient and serviceable than heretofore.

The invention includes the employment of a pair of inner and outer replacing members, which are capable of utilization for replacing rolling stock upon the track rails in either direction of travel.

The invention is characterized by the feature wherein the flange of a wheel of a car or the like that has been derailed is, upon meeting the re-railing member of the pair, positively guided in its path of travel to mount and re-enter tracking relation with the rail, the other member of the pair enabling the opposite wheel to likewise mount the companion rail; and

The invention is also characterized by the feature wherein the crown of the mount part of the re-railing member of the pair is in substantially the same horizontal plane as the upper surface of the rail to be mounted, and is provided with a depression to be travelled by the wheel flange in lowering the wheel tread upon the rail surface.

Other features and advantages of my invention will hereinafter appear.

In the drawing:

Figure 1 is a plan view showing a section of rail track with my improved re-railing device applied thereto.

Fig. 2 is a section on the line 2—2 of Fig. 2.

Fig. 3 is an end view of Fig. 2; and

Fig. 4 is a section on the line 4—4 of Fig. 1.

In carrying out my invention I provide a pair of re-railing devices or members designated respectively by the reference numerals 1 and 2, the member 1 being that which is to be fitted against the inner side of a rail, as 3,

and the member 2 being intended to be fitted 55 against the outer side of the companion rail, as 4.

While the devices in their positions illustrated in the drawing are adapted for service in re-railing rolling stock moving in 60 the direction of the arrow of Fig. 1, it is obvious that they may be used in the same positions with respect to the rails for service in re-railing rolling stock moving in the opposite direction.

The member 1 has a structure including a base 5 whereby it may lie upon the ties as 6, adjacent a rail, said base having a recessed portion 7 to accommodate a portion of the flange 8 of the rail upon which it seats. The 70 side 9 of the member 1 which is adjacent to the rail has a projecting hook element 10 that is adapted to extend over the rail surface and under the outer portion of rail head 11, to thereby engage the rail for the purpose of localizing the device in its operative position.

The upper surface 12 of member 1 is inclined upwardly from its opposite ends, the inclines merging into an intermediate crown 80 portion 12^a, and is provided with guide ribs 13 which extend respectively from the opposite ends of said member, lying in approximate parallelism with the inner edge 14 of the device, these ribs however diminishing 85 inwardly in sectional area and merging into the crown or central portion 12^a of member 1.

The opposite inclines of surface 12 are rearwardly warped toward the center of 90 member 1, and are guarded by a wall 15 which has the horizontal profile of a wide prone V, being in effect a more steep continuation of the inclines, to serve as a guide that co-acts with the flange of a wheel travelling up one 95 of the inclines, for the purpose of urging the wheel toward the rail.

The wall 15, toward its vertex, lies near the linear clearance between the ribs 13, and therefore tends to crowd the wheel flange toward the rail at the outer side of the rib 13 which is in advance thereof; and the member 1, at the respective points between the inner terminal portions of the ribs 13 and the edge 14, is provided with base depressions 16, whereof the forward depression allows the wheel flange, on leaving crown 12^a, to drop down easily alongside the rail

head, so that the tread of the wheel is enabled to ride smoothly onto the rail surface.

The hook element 10 effects its junction 5 with member 1 by means of a web 17 that rises from the edge 14 at the side of the member 1 and comprises a wall which engages the flange of the wheel that is moving over the crown 12^a in its path toward 10 re-tracking upon the rail, thereby aiding to guide the wheel flange into the depression 16. This wall 17 is surmounted by a vertical extension 18 that accentuates the guiding characteristic of wall 17, and serves as 15 a seat upon which the wheel tread may travel.

This wall 17 has the arcuate form indicated, to aid the passage of the wheel flange into depression 16, and to stiffen its structure.

The web or wall 17 must be so disposed as to have its inner face practically in the vertical plane of the inner side of the rail head to be mounted, in order that when a 25 wheel is on the companion rail it will be held truly in position upon the flat upper surface 19 of member 2, and will travel over this surface to drop down into tracking engagement with its rail.

30 The member 1 is provided with a rear base web 20 having engaging means as 21 for the reception of spikes 22 whereby the device may be spiked to the ties.

Variations within the spirit and scope of 35 my invention are equally comprehended by the foregoing disclosure:

I claim:

1. A re-railing device for rolling stock 40 comprising a member having a seating base, its inner side having a straight edge to lie against a rail, a hook element to engage the rail head, the hook element extended by an arcuate web from the inner side of the member, and the member characterized as having 45 its upper surface upwardly inclined from opposite ends, with an intermediate crown portion, that is in substantially the same horizontal plane as the surface of the rail to be mounted, the inclines being 50 warped toward the center and provided with a rear vertical wall-like extension, to crowd

a wheel flange travelling thereover toward the rail, ribs upon the inclined surface which respectively diminish and merge inwardly into the upper surface of the member 55 toward its crown portion, the ribs lying in approximate parallelism with the straight edge of the member, and forming each an inner boundary for a wheel flange that is being crowded over toward the rail, and the member having depressions lying between the terminal portions of the ribs and the arcuate web of the hook element, to co-act therewith and permit a wheel flange to drop 60 easily alongside the rail and thereby permit 65 the wheel tread to engage in track relation with the rail.

2. A re-railing device for rolling stock comprising a member having a seating base, its inner side having a straight edge to lie 70 against a rail, a hook element to engage the rail head, and having an upper, reinforce, guide extension, the hook element extended by an arcuate web from the inner side of the member, and the member characterized as 75 having its upper surface upwardly inclined from opposite ends, with an intermediate crown portion, that is in substantially the same horizontal plane as the surface of the rail to be mounted, the inclines being 80 warped toward the center and provided with a rear vertical wall-like extension, to crowd a wheel flange travelling thereover toward the rail, ribs upon the inclined surface which respectively diminish and merge 85 inwardly into the upper surface of the member toward its crown portion, the ribs lying in approximate parallelism with the straight edge of the member, and forming each an inner boundary for a wheel flange that is being crowded over toward the rail, and the member having depressions lying between the terminal portions of the ribs and the arcuate web of the hook element, to co-act 90 therewith and permit a wheel flange to drop 95 easily alongside the rail and thereby permit the wheel tread to engage in track relation with the rail.

Signed at New York, in the county and State of New York, this 2nd day of September, 1921.

DAVID DWIGHT HOLMES.
